E. Bigelow

E. BIGELOW, OF SPRINGFIELD, MASSACHUSETTS.

Letters Patent No. 89,010, dated April 20, 1869.

IMPROVED ICE-CHEST FOR SODA-APPARATUS AND REFRIGERATORS.

The Schedule referred to in these Letters Patent and making part of the same.

To all whom it may concern:

Be it known that I, E. BIGELOW, of Springfield, in the State of Massachusetts, have invented a new and useful Improvement in the Ice-Chest of Soda-Apparatus and Refrigerators; and I do hereby declare that the following is a full and accurate description of the same, reference being had to the annexed drawings, forming a part thereof, in which—

Figure 1 is a top view of an ice-chest on my improved plan, and

Figure 2, a longitudinal vertical section.

The same letters refer to like parts in both figures.

It is well known that the metallic water-tight lining of ice-chests causes the ice to melt rapidly. This is more particularly the case in the ice-apartment of soda-apparatus, because the ice-chest is quite deep, and presents to the ice in it a very large metallic surface, and the ice being broken in small lumps, and packed against the metallic lining, melts away with great rapidity.

This objection in ice-chests has, in part, been overcome by placing between the metallic water-tight lining of the ice-chest and the ice a lining of felt, flannel, or wood, but to these substances there are serious objections. The felt and flannel are of very fragile texture, easily torn, soon become wet through and musty, and impart a very disagreeable smell to the refrigerator.

If wood is used between the metallic lining of the ice-chest and the ice, it is very liable to warp, and when used of a sufficient thickness, for a lining in the ice-chest of a soda-apparatus, it takes up too much of the space required for a sufficient quantity of ice. In addition to this, when the wood once becomes musty, it is not easily purified.

My invention consists in covering the metal water-tight lining of the ice-chest of a soda-apparatus or refrigerator with a lining of pure sheet gutta-percha, or any other equally indestructible gum, that will act as a non-conductor of heat, be impervious to water, will not mould, and can be readily removed and washed, and replaced in the ice-chest.

In the annexed drawings—

a represents an ice-chest or ice-box formed with the usual metallic water-tight lining *b*, the non-conducting

material *c* being interposed between the outside case and the lining, as is usual in all ice-chests.

To the inside of the metallic water-tight lining, I fit snugly another lining, *d*, made of sheet gutta-percha, and which extends from the bottom to the top of the ice-chest.

The upper edge of all four sides of this lining *d* is formed with a flanch, *e*, which is secured by rivets or otherwise to the under side of a strip of metal, *f*.

These strips of metal extend all around the top edge of the ice-chest, and the flanches *e* and metal strips are each made of a width equal to the thickness of the ice-chest proper.

A flanch, *g*, may be formed at the outer edge of the metal strips, to project down a short distance over the upper edge of the ice-chest, but this will not be required if the inner lining is made to fit snugly all around to the metallic lining.

This inner lining, made from pure sheet gutta-percha, being a good non-conductor of heat, and impervious to water, will preserve the ice for a much longer time than by any other known means; it is flexible, and yet of very tough fibre, and is indestructible, and is inodorous to the extent that it will not impart a disagreeable flavor to any fluids or food placed in contact with it. It can be removed from the ice-chest with great facility, and is easily washed and made pure, by simply using water.

I have described the inner lining *d* as being made of pure sheet gutta-percha, because I deem that substance the best, but it will be obvious that any other gum possessing all, or nearly all, the properties I have specified can be substituted for the gutta-percha, and, therefore, I wish it to be understood that I do not confine myself exclusively to its use.

What I claim herein as new, and desire to secure by Letters Patent, is—

Providing the metallic water-tight lining of ice-chests with an inner lining of sheet gutta-percha, or other equivalent gum, as herein described, and for the purposes set forth.
